CORNER WALL SHELF

Filed Aug. 30, 1945

UNITED STATES PATENT OFFICE

2,465,635

CORNER WALL SHELF

James A. Conterio, Chicago, Ill.

Application August 30, 1945, Serial No. 613,483

4 Claims. (Cl. 211—90)

1

The main objects of this invention are, to provide an improved shelf construction of the type for suspension in the corner of a room, to be used in the supporting of small or light-weight articles in the nature of knick-knacks, vases, and the like; to provide an improved shelf construction of this kind in which the wall-supporting parts are normally urged toward an angular relationship of greater than 90° whereby the shelf will be securely held in place despite severe vibrations to which the walls might be subjected or despite any change in the angular relationship of the walls due to the settling of the building; and to provide an improved shelf construction of this type which can be made of almost any light-weight material, of desired ornamental character, and which can support articles of considerable weight.

A shelf constructed in accordance with this invention, embodying alternate forms of a spring hinge, is shown in the accompanying drawings, in which

Fig. 1 is a perspective view of a shelf, employing the preferred form of spring hinge, showing the relative positions of the parts when the shelf is removed from a wall corner;

Fig. 2 is a plan view of the same;

Fig. 3 is a horizontal cross-sectional view of the shelf taken on the line 3—3 of Fig. 1, but showing it in place in a wall corner;

Fig. 4 is an enlarged fragmentary cross-sectional view taken on the line 4—4 of Fig. 2;

Fig. 5 is an enlarged fragmentary sectional view taken through the corner of the shelf and showing the preferred form of spring hinge arrangement; and

Fig. 6 is a view similar to Fig. 5 but showing a modified form of spring hinge.

A shelf constructed in accordance with this invention comprises, a ledge section 7 on which are formed a pair of supporting parts 8 and 9 having on their backs wall-engaging means 10 whose contact with the walls is made more secure by the pressure of a spring hinge 11.

The ledge section 7 is made up of a pair of sector-shaped members 12 and 13. These are arranged in overlapping relationship so that they may be relatively shifted on an axis 14 coincident with the vertex of the angle of each of the two members. These members are held in their assembled relationship by means of the spring 11, as will more fully hereinafter appear, and a double-headed pin 15 on the member 12 extending through a slot 16 in the member 13.

The supporting parts 8 and 9 are shown in-

2

tegral with the sector-shaped members 12 and 13, being disposed at right angles thereto along the opposite edges thereof. At their forward ends the parts 8 and 9 may be extended, as shown, to form grips 17 and 18 which facilitate the handling of the shelf when it is being placed in or moved from a wall corner. These supporting parts and ledge members may be made as ornamental as taste may dictate.

10 The wall-engaging means 10 is herein shown in the form of tacks. These extend through plates 19 which, in the embodiment herein shown, are riveted at 20 to the respective supporting parts 8 and 9. If preferred, these plates may be spot-welded to the supporting parts. The number of rows of these tacks and the number of tacks in a row will be influenced somewhat by the use to which the corner shelf is to be put.

15 The preferred embodiment of spring 11 is formed with an arcuate part 21 and a pair of angularly-arranged arms 22 and 23. The arcuate part 21 is inserted through slots 24 in the adjacent ends of the supporting parts 8 and 9, which brings the spring arms 22 and 23 into 20 pressing contact with the inner faces of the parts 8 and 9 respectively. Thus, the spring serves as a hinge for the relative shifting of the ledge members 12 and 13 and their integral supporting parts 8 and 9 about an axis 14.

25 In the modification shown in Fig. 6, the spring 11' is without the loop 21 formed in the spring 11 of the preferred modification. The arms 22 and 23 are anchored between the plates 19 and the respective supporting parts 8 and 9. The 30 effect is the same as with the preferred embodiment.

35 In either modification, when the spring 11 is completely unflexed, arms 22 and 23 are disposed at an angle greater than 90°. Thus, when either 40 type of the spring 11 is placed in position with regard to the supporting parts 8 and 9, the spring tends to shift the supporting parts 8 and 9 toward an angle of greater than 90°. Therefore, after the shelf has been placed in position and the 45 tacks have been driven into the wall surface, the spring keeps the supporting parts 8 and 9 in firm contact with the walls. Accordingly, if a building should be subjected to any violent vibrations or if the building should settle and increase the angularity of the walls at the corner, there is small likelihood of the shelf becoming 50 loose, because the spring keeps the arms pressed against the wall surfaces.

When it is desired to place in a wall corner a 55 shelf, embodying this invention, the grips 17

permit the members of the ledge section 7 to be retracted sufficiently to place the shelf in proper position in the wall corner. The spring 11 will cause the tacks 10 to penetrate the wall.

When it is desired to remove a shelf of this kind from a wall corner, it is only necessary to pull the arms 17 and 18 toward each other by pressure on the grips 11.

Other variations and modifications in the details of structure and arrangement of the parts may be resorted to within the spirit and coverage of the appended claims.

I claim:

1. A wall shelf of the class described comprising, a ledge section, a pair of supporting parts disposed along the angular edges of said ledge section, wall-engaging means on said supporting parts, and a spring anchored to said supporting parts to form a hinge connection therefor and normally urging said parts toward an angular relationship of greater than 90° so as to retain said wall-engaging parts in contact with the supporting wall.

2. A wall shelf of the class described comprising, a ledge section, a pair of supporting parts disposed along the angular edges of said ledge section, wall-engaging means on said supporting parts, and a leaf spring having an arcuate portion looped through the adjacent ends of said supporting parts and having oppositely-disposed arms engaging the inner faces of said supporting parts and normally urging them toward an angular relationship of greater than 90° so as to retain said wall-engaging parts in contact with the supporting wall.

3. A corner shelf of the class described comprising, a pair of relatively-shiftable, sector-shaped members constituting a ledge section, a vertical supporting part fixed along one edge of each of said sector-shaped members, wall-engaging means on each of said supporting parts, and

a leaf spring having the oppositely-disposed arms thereof respectively connected to said supporting parts and serving as a hinge therefor and normally urging said parts toward an angular relationship of greater than 90° so as to retain said wall-engaging parts in contact with the respective supporting walls.

4. A corner shelf of the class described comprising, a pair of sector-shaped members constituting a ledge section, one of said sector-shaped members being of approximately 90° angle and the other sector member being slidably supported on said first-mentioned sector member about an axis coincident with the vertex of the angle of both of said sector-shaped members, a vertical supporting part integral with each of said sector-shaped members along one edge thereof, wall-engaging means mounted on the back of each of said supporting parts, and a leaf spring having the oppositely-disposed arms thereof respectively connected to said supporting parts and hingedly connecting them together and normally urging said parts toward an angular relationship of greater than 90° so as to retain said wall-engaging parts in contact with the respective supporting walls.

JAMES A. CONTERIO.
